[57] CLAIM

The ornamental design for a building, substantially as shown and described.

DESCRIPTION

FIG. 1 is a front perspective view of a building showing the new design;

FIG. 2 is an elevational view of the right side thereof; FIG. 3 is a rear view thereof; and,

FIG. 4 is a top view thereof.

The left side of the building is substantially a mirror image of FIG. 2, and the bottom of the building is plain and unornamental.

FIG. 1

FIG. 4
